UNITED STATES PATENT OFFICE.

FRED A. CONRAD, OF MILWAUKEE, WISCONSIN, ASSIGNOR TO AMERICAN LACE PAPER COMPANY, OF MILWAUKEE, WISCONSIN, A CORPORATION OF WISCONSIN.

DESIGN FOR A NAPKIN.

Application filed April 23, 1928. Serial No. 26,435. Term of patent 14 years.

To all whom it may concern:

Be it known that I, FRED A. CONRAD, a citizen of the United States, residing at Milwaukee, in the county of Milwaukee and State of Wisconsin, have invented a new, original, and ornamental Design for Napkins, of which the following is a specification, reference being had to the accompanying drawings, forming part thereof.

In the drawings:

Figure 1 is a plan view of a napkin embodying the design of this invention.

Figure 2 is a detail view in enlarged sec-

tion in the plane indicated at 2—2 in Figure 1.

Like parts are identified by the same reference characters in both views.

The areas 5, 6, and 7, and other like areas indicated in the drawings are higher than such areas as are designated at 8 and 9, which are substantially in the plane of the general area of the napkin.

I claim:

The ornamental design for a napkin substantially as shown and described.

FRED A. CONRAD.
